BURIAL VAULT

Frank Holz, Cleveland, Ohio, assignor to Norborn
S. Holz, Cleveland, Ohio

Application September 27, 1938, Serial No. 231,895

9 Claims. (Cl. 72—7)

The present invention relates to a burial vault or mausoleum of the completely enclosing type wherein the contents, such as a casket, is surrounded on all sides by the walls of the vault, 5 a sealed door being provided for access to the interior of the vault.

One of the fundamental problems in the construction of such a type of burial vault is the provision of a satisfactory water-tight and gas-tight seal around the vault door.

It is, therefore, the general object and nature 10 of my invention to provide a novel construction of burial vault of the type indicated wherein the vault door is positively locked and efficiently sealed in place.

To the accomplishment of the foregoing and related ends, said invention, then, consists of the means hereinafter fully described and particularly pointed out in the claims.

20 The annexed drawing and the following description set forth in detail certain structure embodying the invention, such disclosed means constituting, however, but one of various structural forms in which the principle of the invention 25 may be used.

In said annexed drawing:

Fig. 1 is a vertical sectional view of the door end portion of a burial vault embodying the principle of my invention; Fig. 2 is a half section taken upon a plane normal to that of Fig. 1 and substantially along line 2—2 thereof; and Fig. 3 is a sectional view similar to that of Fig. 1 but showing a modified form of construction.

Now referring more particularly to Figs. 1 and 2, the burial vault shown therein consists of the integral bottom wall 1, two side walls, one of which is indicated at 2, the top wall 3, and a rear end wall which is not shown. A door opening or frame 4 is provided in the front end of the 35 vault for the reception of the door 5. A series of parallel, continuous grooves 6 are provided in the door frame 4 and in registry with similar grooves 7 in the opposed surface of the door 5.

40 A sealing compound pouring gate 8 is provided in the top wall 3 of the vault and communicates with the exterior thereof through the passage 9. It will be noted from Figs. 1 and 2 that the pouring gate 8 is substantially in the form of a truncated pyramid, or inverted funnel, with its bottom side or base joining with the grooves 6. The pouring gate consists of two parts, an upper 45 conical portion 9 and a lower passage 8, which in cross-section resembles a trapezium. It is to be noted that the passage 8 is considerably longer 50 than it is wide, thus permitting the sealing fluid 55

to flow quite readily into the registering grooves 6 and 7. Vertical passages 10 are also provided through the roof 3 of the vault and form a longitudinal extension of the combined or composite space formed by the vertical or side wall 5 portions of the grooves 6 and 7. The cross-sectional dimension of the passage 10 is identical to that of the combined space or groove formed by the grooves 6 and 7. Locking pins or dowels 11 are inserted through the passages 10 and into 10 the vertical side portions of the registering grooves 6 and 7 and thus serve to positively lock and retain the door 5 in position in the door opening or frame 4. The locking pins 11 are 15 preferably composed of a durable, strong material such as steel or iron. The remainder of the grooves 6 and 7 are filled with a sealing compound composed of an asphaltic or bituminous material, such as asphalt or pitch poured in through the passage 9 and gate 8. In order 20 that such sealing compound can be made to fill the bottom, horizontal portions of the grooves 6 and 7, and without causing the formation of air pockets, it is first poured into a level corresponding to the bottom end of the locking pin 11, the 25 latter then inserted in position, and the filling of the remaining or upper portion of the grooves 6 and 7 then completed.

Although the same number of passages 10 and locking pins 11 as that of the grooves 6 and 7 are 30 shown in the accompanying drawing, it should be apparent to those skilled in the art that a fewer number can be employed, such, for example, as only one locking pin 11 on each side.

In the modified form of construction shown in 35 Fig. 3, the sealing compound receiving grooves between the door frame 4' and the door 5' are in the form of contiguous steps or shoulders. Thus the central groove 61 and the contiguous 40 outer groove 62 are provided in the door frame 4' and co-extensive, complementary grooves 71 and 72 are provided in the door 5'. A sealing compound gate 8', with the passage 9', similar to that employed in the form of construction 45 shown in Figs. 1 and 2, is also provided. The bottom edge of the gate 8' is in registry and co-extensive with the outside edges of the innermost groove 61, so that the sealing compound poured in through the passage 9' is properly distributed 50 to all of the grooves 61, 62, 71 and 72.

Other modes of applying the principle of my invention may be employed instead of the one explained, change being made as regards the mechanism herein disclosed, provided the means 55

stated by any of the following claims or the equivalent of such stated means be employed.

I therefore particularly point out and distinctly claim as my invention:

- 5 1. In a burial vault having a door frame and a door, a continuous groove in said frame, a continuous groove in said door, one of said grooves registering with the other to form a passage, other passages extending through the wall of 10 said vault, said other passages forming longitudinal extensions of portions of said grooves, the cross sectional dimensions of said other passages being equal to the combined cross sectional dimensions of the grooves of which they form extensions, locking pins fitting snugly into said 15 other passages and into said portions of said grooves, said pins having cross sectional dimensions similar to but slightly less than said first named cross sectional dimensions, an opening 20 from the exterior of said vault communicating with said grooves, and a sealing compound filling that part of said grooves which is not occupied by said pins.
- 25 2. In a burial vault having a door frame and a door, a continuous semi-circular groove in said frame, a continuous semi-circular groove in said door, one of said grooves being oppositely disposed to the other to form a circular passage, and other circular passages extending through 30 the wall of said vault, said other passages forming longitudinal extensions of portions of said grooves, the cross sectional dimensions of said other passages being equal to the combined cross sectional dimensions of the grooves of which they 35 form extensions, cylindrical locking pins fitting snugly into said other passages and into portions of said grooves, an opening from the exterior of said vault communicating with said grooves, and a sealing compound filling that part of said grooves which 40 is not occupied by said locking pins.
- 45 3. In a burial vault having a door frame and a door, a plurality of continuous grooves in said frame, a plurality of continuous grooves in said door, each groove in said frame registering with each groove in said door to form a plurality of passages and an opening from the exterior of said vault communicating with said passages, other passages extending through the wall of 50 said vault, said other passages forming longitudinal extensions of portions of said grooves, and being located in opposite sides of said vault, the cross sectional dimensions of said other 55 passages being equal to the combined cross sectional dimensions of the grooves of which they form extensions, locking pins fitting snugly into said other passages and into said portions of said grooves, said pins having cross sectional dimensions similar to but slightly less than said first named cross sectional dimensions, an opening from the exterior of said vault communicating with said grooves, and a sealing compound filling that part of said grooves which 60 is not occupied by said pins, said door frame having a pouring gate therein, said gate being immediately above that portion of said grooves between said locking pins, and flaring downwardly and outwardly, said opening from the exterior also flaring downwardly and outwardly and being above said gate and in direct communication therewith.
- 65 4. In a burial vault having a door frame and a door, a plurality of continuous semi-circular grooves in said frame, a plurality of continuous semi-circular grooves in said door, each groove in said frame registering with each groove in said door to form continuous circular passages and an opening from the exterior of said vault 70 communicating with said passages, vertical circular passages through the wall of said vault, each forming a longitudinal extension of the vertical portions of said grooves, the cross sec-

tional dimensions of said vertical circular passages being equal to the combined cross sectional dimensions of the grooves of which they form extensions, a cylindrical locking pin fitting snugly into one of said vertical circular 5 passages and into one of said vertical portions of said grooves on one side of said door, another cylindrical locking pin fitting into one of said vertical circular passages and into one of said portions of said grooves on the other side of 10 said door, and a sealing compound filling those parts of said grooves that are not occupied by said cylindrical locking pins.

5. In a burial vault having a door frame and a door, a continuous groove in said frame, a continuous groove in said door, one of said grooves registering with the other to form a passage, other passages extending through the wall of said vault, said other passages forming longitudinal extensions of portions of said 20 grooves, the cross-sectional dimensions of said other passages being equal to the combined cross-sectional dimensions of the grooves of which they form extensions, locking pins fitting snugly into said other passages and into said 25 portions of said grooves, said pins having cross-sectional dimensions similar to but slightly less than said first named cross-sectional dimensions, an opening from the exterior of said vault communicating with said grooves, and a sealing 30 compound filling that part of said grooves which is not occupied by said pins, said door frame having a pouring gate therein, said gate being immediately above that portion of said grooves between said locking pins, and flaring downwardly and outwardly.

6. In a burial vault having a door frame and a door, a continuous groove in said frame, a continuous groove in said door, one of said grooves registering with the other to form a 40 passage, other passages extending through the wall of said vault, said other passages forming longitudinal extensions of portions of said grooves, the cross-sectional dimensions of said other passages being equal to the combined cross-sectional dimensions of the grooves of which they form extensions, locking pins fitting snugly into said other passages and into said 45 portions of said grooves, said pins having cross-sectional dimensions similar to but slightly less than said first named cross-sectional dimensions, an opening from the exterior of said vault communicating with said grooves, and a sealing compound filling that part of said grooves which is not occupied by said pins, said door frame 50 having a pouring gate therein, said gate being immediately above that portion of said grooves between said locking pins, and flaring downwardly and outwardly, said opening from the exterior also flaring downwardly and outwardly and being above said gate and in direct communication therewith.

7. In a burial vault having a door frame and a door, a continuous groove in said frame, a continuous groove in said door, one of said 65 grooves registering with the other to form a passage, other passages extending through the wall of said vault, said other passages forming longitudinal extensions of portions of said 70 grooves, the cross-sectional dimensions of said other passages being equal to the combined cross-sectional dimensions of the grooves of which they form extensions, locking pins fitting snugly into said other passages and into said 75 portions of said grooves, said pins having cross-

sectional dimensions similar to but slightly less than said first named cross-sectional dimensions, an opening from the exterior of said vault communicating with said grooves, and a sealing compound filling that part of said grooves which is not occupied by said pins, said door frame having a pouring gate therein, said gate being immediately above that portion of said grooves between said locking pins, and flaring downwardly and outwardly, said gate being materially longer than it is wide, whereby sealing compound may readily flow to the vertical portions of said grooves.

8. The method of sealing a burial vault door in a door frame which comprises forming a groove in the perimeter of the door, forming a groove in the door frame, in such manner that such grooves register, forming extensions of the vertical portions of said grooves through the wall of said vault, then pouring sealing compound into said grooves to a predetermined level, then inserting locking pins in said extensions and vertical portions of said grooves, said locking pins having substantially the same diameter as said grooves, compressing said sealing

compound and forcing the same into intimate contact with said grooves and then filling the remaining parts of said grooves with sealing compound.

9. The method of sealing a burial vault door in a door frame which comprises forming a groove in the perimeter of the door, forming a groove in the door frame, in such manner that such grooves register, forming extensions of the vertical portions of said grooves through the wall of said vault, then forming a pouring gate above said grooves and between the vertical portions thereof, then pouring sealing compound into said gate so that the same may flow down and fill up the bottom horizontal portions of said grooves and part of the vertical portions thereof, then inserting locking pins of the same diameter as said grooves in said vertical portions and extensions and tamping said previously poured compound into place, then filling said pouring gate with sealing compound, so that the same may flow into that part of said grooves not occupied by said locking pins.
